UNITED STATES PATENT OFFICE.

WILLIAM F. KELLETT, OF CHICAGO, ILLINOIS.

DESIGN FOR A PLASTER CENTER-PIECE.

SPECIFICATION forming part of Design No. 14,325, dated September 25, 1883.

Application filed December 1, 1882. Term of patent 14 years.

To all whom it may concern:

Be it known that I, WILLIAM F. KELLETT, a citizen of the United States, residing at Chicago, in the county of Cook and State of Illinois, have invented and produced a new and original Design in Plaster Center-Pieces for Rooms, of which the following is a true and correct specification, reference being had to the accompanying engravings, forming a part 10 thereof, and in which—

Figure 1 represents an arrangement in my design of the frame, containing heart-shaped panels formed of leaves in scroll and scallop, with wings composed of masses of geranium-leaves bounded by crocketed perpendicular arches and rosettes in threes on opposite sides. Fig. 2 shows heart-shaped panels of fruit.

Both these views are deemed necessary in order to fully illustrate my design. In designs like this it is desirable to show diversity in minor details. For that reason I do not confine myself to the same details of construction of the panels in this design, nor to the same arrangement of wings connected with the 25 frame.

My design is fully illustrated in the engravings; and it consists of a molded frame, A, containing within it four heart-shaped panels having wings connected therewith, of rosettes D, 30 two open and one in husk, combined together in threes, as shown in Fig. 1, or masses of con-

ventional geranium-leaves bounded by crocketed perpendicular arches, marked C in the engraving, as shown in Fig. 1, with a rosette, E, in quarters in the center of the frame. 35

In this design the panels are all heart-shaped, and may be formed by heart-shaped leaves B, in form of scroll and scallop, as shown in Fig. 2; or they may be fruit-panels, as shown in Fig. 2; or both styles of panels 40 may be combined in one design.

In this design the wings connected with the molded frame may have the crocketed arch and geranium-leaves on two opposite sides, with rosettes arranged, as before described, on 45 the other two sides, as shown in Figs. 1 and 2.

The different arrangements shown in this design can be used as the room to be decorated may require.

I claim—

A design for a plaster center-piece, consisting of a molded frame containing within it a central rosette in quarters, four heart-shaped panels of leaves in scroll and scallop, with wings formed of rosettes in sets of three, and 55 conventional geranium-leaves bounded by crocketed perpendicular arches, substantially as shown and described.

WILLIAM F. KELLETT.
